UNITED STATES PATENT OFFICE.

PETER N. TROUT, OF ROANOKE, VIRGINIA.

HEADLIGHT-ACTUATING MECHANISM FOR LOCOMOTIVES.

1,112,577.

Specification of Letters Patent.

Patented Oct. 6, 1914.

Application filed December 8, 1913. Serial No. 305,383.

To all whom it may concern:

Be it known that I, PETER N. TROUT, citizen of the United States, residing at Roanoke, in the county of Roanoke and State of Virginia, have invented certain new and useful Improvements in Headlight-Actuating Mechanism for Locomotives, of which the following is a specification.

My invention relates to locomotives and particularly to the headlights thereof.

My general object is to provide means for automatically rotating a headlight in a plane parallel to the roadbed when the locomotive strikes a curve, this means operating to rotate the headlight in a direction to correspond with the direction of curvature of the track.

A further object of my invention is the provision of gravity operated means operatively connected to the headlight to rotate the latter, this means being of such character that a relatively heavy weight may be used whereby a positive actuation of the headlight will be secured when the locomotive strikes a laterally inclined portion of the track upon a curve.

A further object of the invention is to so mount the pendulum or weight actuating the headlight that its proper lateral swinging movement shall not be affected by the grade of the track so that the pendulum shall operate as well upon an up grade or down grade as upon a level.

A still further object is to provide a very simple mechanism to the ends above stated, readily put in place upon any locomotive, not easily put out of order and readily repaired.

Other objects will appear in the course of the following description.

My invention is illustrated in the accompanying drawings wherein:

Figure 1 is a side elevation of the forward end of the locomotive showing my improved headlight actuating mechanism applied thereto. Fig. 2 is a front elevation of a locomotive provided with my headlight actuating mechanism, the locomotive being shown as laterally inclined. Fig. 3 is a front elevation of the pendulum and shaft, the mechanism being broken away. Fig. 4 is a diagrammatic perspective view showing the headlight, the pendulum and the operating connections between the pendulum and the headlight.

Corresponding and like parts are referred

to in the following description and indicated in all the views of the accompanying drawings by the same reference characters.

Referring to these drawings, A designates a locomotive of any suitable character and B the forward frame thereof carrying the cowcatcher. The headlight 2 is mounted upon the forward end of the locomotive, preferably in front of the boiler upon a vertical shaft or spindle 3. This shaft passes through supporting brackets 4 and 5 which are shown as projecting from the front end of the boiler, the shaft being shown as provided with a bearing member 6 which rests upon the uppermost bracket 4. It will be understood that I do not wish to limit myself to the precise construction illustrated as regards the support for this shaft.

The shaft at its lower end is provided with an outwardly projecting arm 7 and the lower end of the shaft is supported below this arm upon any suitable bracket 8 which is attached to the platform carried upon the front frame. Mounted upon this platform at opposite sides of the shaft are the upwardly extending brackets 9, and carried upon each of these brackets are the horizontally disposed pulleys 10 over each of which passes a cable 11. Each of these cables 11 at its forward end is attached to the forward end of the arm 7, the pulleys being in line with this arm. Mounted upon the side frames of the locomotive rearward of the cylinders and supported in any suitable manner are the vertical shafts 12 upon which are mounted the pulleys 13 over which the cables 11 pass.

Mounted in bearings in the side frames C of the locomotive or rotatably supported in any suitable manner is a transverse shaft 14 which is located between the side frames approximately in line with the centers of the pulleys 13. This shaft at its middle carries a rectangular yoke 15 within which is pivoted for lateral movement the upper end of a weight or pendulum 16. The lower portion of this pendulum is relatively large and the upper portion is narrowed to form a neck which extends up into the yoke and which is pivoted thereto upon trunnions 17 or is pivotally connected to the yoke by like instrumentalities.

Extending upward from the weight 16 is the arm 18 which is provided with laterally projecting eyes 19 to which the inner ends of the cables 11 are attached. It will be

noted that the yoke 15 forms a gimbal-joint within which the weight 16 is mounted so that the weight 16 may swing either in a vertical plane extending longitudinally of the locomotive or in a vertical plane extending transversely of the locomotive.

The operation of my invention will be obvious. When the locomotive strikes a curve, the necessary inclination of the roadbed will cant the locomotive toward the inner side of the curve. This will cause the lower end of the weight to swing toward the inner side of the curve, and this will draw upon one of the cables 11 while slackening the other cable, thus causing the rotation of the spindle 3 and the consequent rotation of the headlight in the same direction as the direction of the curve. When the locomotive has again passed upon a level track, the weight will swing back to its median position and thus cause the headlight to be returned to a position where it will project the light directly ahead of the locomotive and in line therewith. The degree of rotation of the headlight will, of course, depend upon the degree of swing given to the weight 16.

It will be noted that inasmuch as the weight 16 is mounted in the yoke 15 which in turn is rotatably mounted upon the shaft 14, the weight may swing in a vertical plane coincident with the longitudinal axis of the locomotive, so that the weight is always held vertically disposed. Thus no matter what the grade of the road may be, and whether the roadbed is inclined downward or upward or is upon a level, the weight or pendulum 16 always has free lateral swinging action. The forward or rearward inclination of the pendulum 16 will not effect a rotation of the headlight for the reason that it will simply act to tighten up upon the cables 11 and inasmuch as this tightening action will be the same for both cables 11, there will be no rotative pull in one direction or the other upon the spindle of the headlight.

Inasmuch as the pendulum is disposed beneath the locomotive, a relatively large and heavy pendulum may be used which will not be readily affected by any slight rocking of the locomotive but which will be positively affected by any lateral cant of the locomotive. By placing the weight beneath the locomotive, a maximum action of the pendulum is secured and repairs to the mechanism may be readily effected at any time.

There is no intricate mechanism connected with my lamp actuating device, the parts are simple, may be readily replaced when broken and may be readily repaired at any time.

What I claim is:

1. The combination with a locomotive, of a headlight rotatably mounted thereon for rotation in an approximately horizontal

plane, a pendulum swingingly supported below the boiler of the locomotive and between its side frames, an arm projecting in line with the longitudinal axis of the locomotive and operatively connected to the headlight, flexible connections passing from said arm to the pendulum, and pulleys over which said flexible connections pass.

2. The combination with a locomotive, of a headlight, a vertical spindle for the headlight rotatably supported upon the locomotive and having a forwardly projecting arm, oppositely disposed pulleys disposed one on each side of said spindle, a pendulum pivotally supported beneath the boiler of the locomotive and having an upwardly extending arm, and flexible connections passing from said upwardly extending arm to the arm of the headlight spindle.

3. The combination with a locomotive including a boiler and side frames, of a headlight, a vertical spindle upon which the headlight is mounted and supported for rotation upon the locomotive and having a forwardly extending arm, a pendulum swingingly mounted between the side frames of the locomotive and beneath the boiler thereof and having an upwardly extending arm, pulleys supported on each side of the locomotive opposite said pendulum, pulleys supported on each side of the spindle opposite the arm thereof, and flexible connections passing from the upper end of the pendulum above its pivotal point over said pulleys to said arm.

4. The combination with a locomotive, of a headlight rotatably mounted thereon for rotation in an approximately horizontal plane, a pendulum pivotally supported on the locomotive for movement in a plane transverse thereto and for movement in a plane approximately coincident with the longitudinal axis of the locomotive, and operative connections between the pendulum above its pivotal axis and said headlight whereby the latter will be rotated upon a lateral swinging of the pendulum relative to the locomotive.

5. The combination with a locomotive, of a headlight rotatably mounted thereon for rotation in an approximately horizontal plane, a transverse shaft including a yoke and supported upon the locomotive frame for movement in a plane parallel to the longitudinal plane of the locomotive, a pendulum pivoted in said yoke for movement transverse to the locomotive, and operative connections between the upper end of said pendulum above its pivotal point and said headlight whereby the latter may be rotated in one or the other direction upon a lateral swinging motion of the pendulum relative to the locomotive.

6. The combination with a locomotive including a boiler and oppositely disposed side

frames, of brackets projecting from the forward end of the boiler, a vertical spindle mounted in said brackets for rotation, a headlight carried upon the upper end of the spindle, an arm projecting from the lower end of the spindle, a shaft mounted upon the side frames of the locomotive below the boiler and including a yoke, a weight pivotally mounted in said yoke for lateral swinging movement, the weight above its pivotal point being upwardly extended to form an arm, pulleys mounted

upon the locomotive on each side opposite said arm, pulleys mounted upon the forward end of the locomotive on each side of said spindle arm, and flexible connections passing from the weight arm over said pulleys on each side to the spindle arm. 15

In testimony whereof I affix my signature in presence of two witnesses.
